ELASTIC FLUID TURBINE POWER PLANT

Homer R. Reese, Springfield, Pa., assignor to Westinghouse Electric Corporation, a corporation of Pennsylvania

Filed Feb. 27, 1959, Ser. No. 54,762

Term of patent 14 years

(Cl. D55—1)

Fig. 1 is a perspective view taken from one side and one end of an elastic fluid turbine power plant embodying my new design; and

Fig. 2 is a perspective view taken from the opposite side and opposite end of an elastic fluid turbine power plant.

The dominant features of my design reside in the portions shown in full lines.

I claim:

The ornamental design for an elastic fluid turbine power plant, substantially as shown and described.
